UNITED STATES PATENT OFFICE.

FERDINAND E. LIBENOW, OF SPOKANE, WASHINGTON, ASSIGNOR OF TWO-THIRDS TO DANIEL J. MUNN, OF NEW WESTMINSTER, CANADA.

DESIGN FOR A LANTERN.

SPECIFICATION forming part of Design No. 33,288, dated October 2, 1900.

Application filed August 20, 1900. Serial No. 27,503. Term of patent 3½ years.

To all whom it may concern:

Be it known that I, FERDINAND E. LIBENOW, a citizen of the United States, residing at Spokane, in the county of Spokane and State of Washington, have invented and produced a new and original Design for Lanterns; and I do hereby declare the following to be a full, clear, and exact description of the same, reference being had to the accompanying drawings, forming a part thereof, in which—

Figure 1 is a side elevation of my design for a lantern. Fig. 2 is a horizontal section taken on the line 2 2 of Fig. 1.

My design embodies a representation of a body portion having a cylindrical shape and consisting of a lower part *a*, having straight sides *a'*, which merge at the lower end into a bottom member *a*². The upper ends of the sides *a'* merge with a series of horizontal beads *b*, which taper inward to produce a shoulder or bulging part *b*', which ends at the lower end of an upper body portion *c*, which is of less diameter than the part *a*. The sides of the portion *c* terminate at the upper end in an annular bead *c*', from which extends

inwardly a curved crown portion *d*, which portion *d* terminates at an annular bead *e*, which forms the base ornamentation for a vertically-extending cap or chimney-like portion *f*, the sides walls *f'* of which end at the top part *f*² and at one side of the portion *f* have a laterally-extending handle ornamentation *d*.

The upper part *c* of the body has a series of ornamentations, (indicated by *h*), each consisting of a set of openings having the general shape of the letter I, and the bottom part *a* of the body has ornamentations *i* in the nature of a series of openings arranged in a circular form.

What I claim is—

The design for a lantern, substantially as herein shown and described.

In testimony whereof I affix my signature in presence of two witnesses.

FERDINAND E. LIBENOW.
